(57) **CLAIM**

The ornamental design for a laser printer as shown and described.

DESCRIPTION

Fig. 5.1 is a front elevational view of a laser printer showing our new design;

Fig. 5.2 is a rear elevational view thereof;

Fig. 5.3 is a left side elevational view thereof;

Fig. 5.4 is a right side elevational view thereof;

Fig. 5.5 is a top plan view thereof; and

Fig. 5.6 is a perspective view thereof.

The broken lines immediately adjacent to the claimed areas depict the bounds of the claimed design, while all other broken lines are directed to environment. The broken lines form no part of the claimed design.
